UNITED STATES PATENT OFFICE.

ALBERT E. HANSEN, OF CHICAGO, ILLINOIS.

DESIGN FOR A LOOP-AERIAL FRAME.

Application filed March 21, 1927. Serial No. 21,235. Term of patent 3½ years.

To all whom it may concern:

Be it known that I, ALBERT E. HANSEN, a citizen of the United States, and a resident of Chicago, county of Cook, and State of Illinois, have invented a new, original, and ornamental Design for a Loop-Aerial Frame, of which the following is a specification, reference being had to the accom-

panying drawing, forming a part thereof, and wherein a perspective view of the loop-aerial frame is shown.

I claim:

The ornamental design for a loop aerial frame, substantially as shown.

ALBERT E. HANSEN.
